(57) **CLAIM**

The ornamental design for a bolt, as shown and described.

DESCRIPTION

The file of this patent contains at least one reproduction/photograph executed in color. Copies of this patent with color reproduction(s)/photograph(s) will be provided by the Office upon request and payment of the necessary fee.

1. Bolt

1.1 is a perspective view of a bolt showing our new design;

1.2 is a front elevational view thereof;

1.3 is a rear elevational view thereof;

1.4 is a right side elevational view thereof;

1.5 is a left side elevational view thereof;

1.6 is a top plan elevational view thereof; and

1.7 is a bottom plan elevational view thereof.

The red colored showing of the hexagonal cap illustrates portions of the bolt and forms no part of the claimed design.

1 Claim, 7 Drawing Sheets

(7 of 7 Drawing Sheet(s) Filed in Color)
